END STOP FOR SEPARABLE FASTENERS

Davis Marinsky and Louis H. Morin, Bronx, N. Y.

Application June 26, 1942, Serial No. 448,530

11 Claims. (Cl. 24—205)

This invention relates to end stops for separable fastener stringers, and more particularly the invention relates to an end stop wherein a plurality of links at adjacent stringer ends are joined together, and to each other, by means engaging coupling ends of said links to impart a substantially arc shaped contour to said stringer ends, and to form of said stringer ends a closed loop limiting movement of a slider in the direction thereof. The novel features of the invention will be best understood from the following description when taken together with the accompanying drawing in which certain embodiments of the invention are disclosed, and in which the separate parts are designated by suitable reference characters in each of the views and in which:

Fig. 1 is a plan view of an end stop showing one adaptation of our invention, and having part of the structure broken away; and

Fig. 2 is a partial section substantially on the line 2—2 of Fig. 1.

In the construction of end stops for separable fasteners to be used on closures wherein the stringer tapes are brought together beyond the end links, adjacent the wide or web end of the slider it has been customary to employ supplemental means engaging the tapes to draw the same together in the desired manner. Such supplemental means permanently attached to the tapes can be removed only with difficulty, and such removal generally results in damage to the tape and impairment of subsequent use of the fastener.

It is the purpose of the present invention to dispense with supplemental devices attached to the tapes and to unite the tape ends to form an end stop to cooperate with the web end of a slider by utilizing means directly engaging a plurality of links of each stringer in a manner to impart a substantially arcuate contour to said links in drawing toward each other those farthest removed from the slider.

In Fig. 1 of the drawing we have shown end portions of stringer lengths 10 and 11 having links 12 and 13 arranged along opposed edges thereof. As shown in the drawing, the stringers are on a continuous tape 14, having a beaded edge 15 for supporting the links 12 and 13 and which is folded back upon itself in the manner indicated to bring the two stringers into juxtaposition. It will be understood in this connection that the invention applies equally to a construction wherein the stringers are arranged on independent tapes. The slider 16 is shown

in operative engagement with the links 12 and 13, a part of the slider being broken away to show the web 17 thereof.

The coupling ends 18 of the links 12 and 13 are provided with apertures 19 passing therethrough in a direction parallel to the beaded edge 15 of the tape. In the construction shown in the drawing the apertures 19 form in conjunction with the projections 20, the inter-locking means between links 12 and 13 of co-acting stringers, said links being double acting. It will be understood, however, that the invention is not limited to this construction, but links of any type and kind may be fashioned to provide apertures such as the apertures 19 through the coupling ends thereof.

Arranged in the apertures 19 of a plurality of links 12 and 13 adjacent the ends of the stringers is a strand-like member 21 adapted to draw the links into an arcuate contour substantially as indicated in the drawing. For purposes of illustration the member 21 has been indicated as a wire having the ends thereof offset or flattened as at 22 to retain the member 21 against accidental displacement from the links 12 and 13 engaged thereby. It should be noted in this connection that the offset or flattened portions 22 are fashioned while the links 12 and 13 engaged by the member 21 are urged in the direction of each other, thereby tending to draw the end links 12a and 13a toward each other in the manner indicated, and after the offsets 22 are formed the links will thereafter be retained in the substantially arcuate contour by the member 21.

While for purposes of illustration the member 21 has been shown and described as a wire, it will be understood that any strand-like member may be employed having means equivalent to the offsets 22 for retaining the member in connection with a plurality of links 12 and 13, while at the same time drawing the coupling ends 18 of the links toward each other in the manner indicated, thereby bringing the beaded edge portions 15 of the stringers into juxtaposition beyond the end links 12a and 13a.

In the construction shown in the drawing wherein the stringers are on a single continuous tape 14 the folded portion 14a of the tape may be secured to the main portion of the tape 14 by a line of stitching 23, which line of stitching will operate to retain the beaded edges 15 in juxtaposition. It will be understood in this connection that if the stringers constituted separate tapes, it might be desirable to stitch to-

gether the beaded edges 15 beyond the end links 12a, 13a in substantially the position of the line of stitching 23. Such stitching would not constitute an essential part of the end stop construction, but would merely serve to maintain alignment of the tapes beyond the end stop.

The showing in the drawing constitutes but one adaptation of our invention, and it will be understood that it is within the scope of our invention to employ any means for coupling and drawing together a plurality of links at the ends of adjacent stringers to impart to said links a substantially arcuate contour while at the same time forming a closed loop between said stringers which is adapted to be closely engaged by the web 17 of a slider in the fully closed position thereof on the stringers.

Having fully described our invention, what we claim as new and desire to secure by Letters Patent is:

1. An end stop for separable fasteners adapted to be engaged by the web end of a slider in the fully closed position thereof on the fastener, said end stop comprising means directly engaging a plurality of links at end portions of adjacent stringers and supporting said links in a substantially arcuate closed loop contour.

2. An end stop for separable fasteners adapted to be engaged by the web end of a slider in the fully closed position thereof on the fastener, said end stop comprising means directly engaging a plurality of links at end portions of adjacent stringers and supporting said links in a substantially arcuate closed loop contour, and means retaining said first named means against displacement from said links.

3. An end stop for separable fasteners adapted to be engaged by the web end of a slider in the fully closed position thereof on the fastener, said end stop comprising means directly engaging a plurality of links at end portions of adjacent stringers and supporting said links in a substantially arcuate closed loop contour, and said first named means comprising a strand-like member arranged in apertures in the coupling end portions of said links.

4. An end stop for separable fasteners adapted to be engaged by the web end of a slider in the fully closed position thereof on the fastener, said end stop comprising means directly engaging a plurality of links at end portions of adjacent stringers and supporting said links in a substantially arcuate closed loop contour, means retaining said first named means against displacement from said links, and said first named means comprising a strand-like member arranged in apertures in the coupling end portions of said links, said member assuming a substantially U shaped contour, and said second named means comprising offset ends on said member preventing removal of the links therefrom.

5. A closed loop end stop for separable fasteners of the class described, said end stop comprising a plurality of end links on adjacent

stringers having apertures formed longitudinally of said stringers, means extending through said apertures adapted to join the coupling portions of said links, and means retaining said first named means against accidental displacement from said links.

6. In separable fasteners employing stringers, said stringers comprising links spaced longitudinally of a tape edge, the links having coupling portions protruding beyond the tape edges, the coupling portions of the links of each stringer having apertures extending there-through and a strand-like coupling element arranged in the apertures of predetermined links of both stringers for joining said stringers.

7. In separable fasteners employing stringers, said stringers comprising links spaced longitudinally of a tape edge, the links having coupling portions protruding beyond the tape edges, the coupling portions of the links of each stringer having apertures extending there-through, a strand-like coupling element arranged in the apertures of predetermined links of both stringers for joining said stringers, and means retaining the strand against displacement from said links.

8. The combination with the coupling end portions of the links of opposed stringers of a separable fastener, of means engaging predetermined links of each stringer and bridging adjacent links of said stringers for uniting said opposed stringers while maintaining said links disengaged from each other.

9. The combination with the coupling end portions of the links of opposed stringers of a separable fastener, of means engaging predetermined links of each stringer and bridging adjacent links of said stringers for uniting said opposed stringers, said means comprising a U shaped member engaging recessed portions of said links, and means retaining said member against displacement from said links.

10. In separable fasteners, the combination with widely spaced link chains on a single mounting tape, of a coupling member engaging adjacent links of said chains, for coupling the chain ends in close proximity to each other but with links disengaged from each other and means retaining the coupling member against displacement from said links.

11. A fastener of the class described comprising double acting scoops of common construction mounted on a single tape, said tape having a fold intermediate the ends thereof forming two series of scoops in juxtaposed relation for coupling and uncoupling, said scoops having apertures therein formed longitudinally of said tapes; a plurality of scoops adjacent said fold having substantially U-shaped means extending through said apertures and maintaining said links in a substantially U-shaped contour and thereby forming an end stop.
